UNITED STATES PATENT OFFICE.

JUSTUS R. KINNEY, OF JAMAICA PLAIN, MASSACHUSETTS.

DRAINING DEVICE.

Application filed April 27, 1925. Serial No. 26,054.

This invention relates to draining devices, particularly adapted for use by surgeons in draining bladders and similar sacs of the body after surgical operations, and has for 5 its object the production of an inflatable tube adapted to be placed upon a catheter and inserted into an incision and then inflated until the wall of said tube is forced into intimate contact with the wall of said incision and 10 thereby prevent any discharge from the sac except that which passes through the catheter.

This object is attained by the device illustrated in the accompanying drawings.

15 For the purpose of illustrating the invention, one preferred form thereof is illustrated in the drawings, this form having been found to give satisfactory and reliable results, although it is to be understood that 20 the various instrumentalities of which the invention consists can be variously arranged and organized, and the invention is not limited to the precise arrangement and organization of these instrumentalities as herein shown and described except as required by 25 the scope of the appended claims.

Of the drawings:

20 Figure 1 represents an elevation of a device embodying the principles of the present invention.

Figure 2 represents a longitudinal section of same mounted upon a catheter and before inflation, and

35 Figure 3 represents a longitudinal section of the device inserted into an incision and inflated, the catheter on which it is mounted being shown in elevation.

Similar characters indicate like parts 40 throughout the several figures of the drawings.

In the drawings 10 is a catheter which 45 may be of any usual construction and on which the device embodying the present invention is adapted to be mounted intermediate its ends.

This device consists of an inflatable tube 11 having two stretchable necks 12, 13 preferably disposed at the opposite ends thereof as shown in the drawings.

50 Near the neck 13 the tube 11 has extending therefrom a pipe 14 through the bore of which air or liquid is adapted to be forced in order to inflate the tube.

55 The necks 12, 13 are made of considerably less diameter than the diameter of the

catheter on which the tube 11 is to be mounted.

When the tube 11 is to be used the necks 12, 13 are stretched in any well known manner to permit the insertion therethrough of 60 the catheter 10.

These necks 12, 13 when on the catheter will bind upon the outer wall of the catheter sufficiently to prevent the escape of any of 65 the contents of the tube 11.

It is preferable, however, in mounting the tube 11 upon the catheter 10 to turn these necks 12, 13 inwardly into the tube 11 as indicated in Fig. 2.

By so doing it is obvious that the pressure 70 upon these inturned necks when the tube 11 is inflated will more securely bind the necks upon the catheter and thereby more effectively prevent leakage of the contents of the tube.

75 The ends of the necks 12, 13 are provided with the beads 15 to strengthen these necks at this point and for a similar reason the outer end of the laterally extending pipe 14 is provided with a bead 16.

80 As shown in the drawings the catheter 10, for convenience, is provided with a perforated bulb 17 for insertion into the sac to be drained while the outer end of the catheter is preferably provided with a bead 18 to 85 facilitate in retaining thereon a flexible tubing through which the contents of the sac may be drained into some form of receptacle.

85 After a surgical operation has been performed it is quite necessary in many cases to 90 artificially drain a bladder, sac, or canal, and this is done by a catheter or similar tubular member.

95 This catheter, however, never fits the incision or mouth of the sac and as a consequence much of the contents of the sac leaks therefrom outside of the catheter and spreads over the body of the patient, making it necessary to cover the body with sponges made of absorbent gauze to care for 100 all discharge not passing through the bore of the catheter.

105 On account of this leakage the patient must lie upon a rubber blanket which in itself is very objectionable, but the greatest disadvantage is the fact that moistened condition of the body often causes bed sores.

110 The present invention is designed to obviate these and other difficulties attending the methods heretofore in use.

The manner in which the device is used is as follows.

The tube 11 having been mounted upon some form of catheter as shown in Fig. 2 is inserted into an incision in the body as indicated in dotted lines at 19.

The pipe 14 is then connected to a syringe or similar device by which air or liquid may be forced into the tube 11 to stretch and inflate it as shown in Fig. 3.

The flexible discharge tubing is secured to the other end 18 of the catheter.

As soon as the tube 11 has been inflated the pipe 14 is closed in some manner so that the 15 contents of the tube 11 cannot escape.

Both the tube 11 and pipe 14 are made of very thin material and the simplest way of closing the pipe 14 after the inflation has been completed is by twisting the pipe 14, 20 wrapping it around the protruding end of the catheter and then placing thereon a rubber band 20.

This having been done there is no escape for the contents of the tube 11 and portions 25 thereof 21 will be forced into such intimate contact with the wall of the incision 19 that there can be absolutely no leakage from the sac, the thin material of the tube being forced into every irregularity in the wall 30 of the incision.

For the inflation of the tube 11 air will be used generally, but it is quite obvious that in some cases and under some conditions it may be desirable to use a liquid under varying degrees of temperature.

When this device is in use the patient is kept perfectly clean and free from all moisture due to leakage of the contents of the particular sac being drained.

40 The shape of the member 11 may be varied to suit different conditions.

It is believed that the operation and many advantages of the invention will be understood without further description.

45 Having thus described my invention, I claim—

1. The combination of a catheter for draining a sac through an incision an inflatable tube for enclosing the catheter intermediate its ends said tube being adapted to extend beyond the opposite ends of said incision; and means for inflating the tube to cause its outer wall to bear against the wall of the incision and the adjacent outer and inner walls of the portion of the body in which the incision has been made. 50

2. The combination of a catheter for draining a sac through an incision; an inflatable device for closing the incision adapted to be disposed upon said catheter and provided with a lateral flexible pipe extending laterally from the wall thereof and through which the device may be inflated and pressed against the wall of said incision throughout its entire length and the surfaces 60 adjacent the opposite ends thereof. 65

3. The combination of a catheter for draining a sac through an incision; an inflatable member for closing the incision having at its opposite ends inturned stretchable necks surrounding and gripping said catheter; a flexible pipe near one end of said member providing means for inflation and adapted to be wound about the outer end of the catheter; and means for retaining the wrapped portion of the pipe upon said outer end. 70 75

4. The combination of a catheter for draining a sac through an incision; an inflatable member for closing the incision having at its opposite ends inturned stretchable necks surrounding and gripping said catheter; a flexible pipe near one end of said member providing means for inflation and adapted to be wound about the outer end of the catheter; and an elastic band for retaining the wrapped portion of the pipe upon said outer end. 80 85

Signed by me at 746 Old South Bldg., Boston, Mass., this 25th day of April, 1925.

JUSTUS R. KINNEY.
